UNITED STATES PATENT OFFICE.

FRANKLIN F. HAGGENMULLER, OF NEW YORK, ASSIGNOR TO EMILINE BISHOP, OF BROOKLYN, NEW YORK.

METHOD OF PRODUCING LITHOGRAPHIC DRAWINGS.

SPECIFICATION forming part of Letters Patent No. 494,859, dated April 4, 1893.

Application filed January 27, 1892. Serial No. 419,383. (No specimens.)

To all whom it may concern:

Be it known that I, FRANKLIN F. HAGGENMULLER, of the city, county, and State of New York, have invented a new and Improved 5 Method for Producing Lithographic Drawings, of which the following is a full, clear, and exact description.

The invention relates to lithography, and its object is to provide a new and improved 10 method for producing in a very simple and rapid manner, lithographic drawings on stones or plates.

According to an old and well known method, a stippled surface has been produced upon 15 a lithographic stone which was subsequently grained (by use of sand). But, in the graining operation, the points of the stippling are abraded too much so that the surface of the stone as a whole is rendered uneven and consequently imperfect for lithographic printing. This is the principle defect which I have remedied by my method, and the chief distinction of the latter from the old method above referred to lies in this, that I first produce the 25 stippled surface and then transfer an impression of it upon a previously-prepared grained surface. By this and the subsequent operations hereinafter specified I produce a superior printing surface and thus attain superior 30 effects in the prints taken from it.

In carrying out my method, I take a lithographic stone having a flat smooth surface, and I produce thereon an even stipple, by hand, with lithographic ink. From this stippled 35 surface I now take a full impression by means of lithographic transfer paper, with acid-resisting ink, and this impression is transferred to a stone having a grained surface of the usual character. The next step consists in 40 dusting the grained surface to which the transfer has thus been made with finely-powdered asphaltum, or some other gum capable of protecting the stippling from effect of the acid which (as the next step) is applied to the surface 45 for etching it, in order that the stippling may be left in slight relief. To state more in detail this part of the operation, I will add that the asphaltum adheres only to the stippling, and all the remaining portion is easily 50 removed by means of a piece of soft cloth, or

a brush. The nitric acid employed to effect the etching is thin solution with gum, the usual preparation employed for etching on lithographic stones. The gum is used for the usual purpose, namely, solely to temper the 55 action of the acid.

When the etching has progressed sufficiently—that is to say—when it has eaten down more or less all the surface save that portion which the stipple ink protects, the 60 stippling being thus left in slight relief, the stone is washed with turpentine—in the usual way—to remove the ink from the stippling or raised points. The next step consists in washing the stippled surface with acetic acid, 65 diluted with water, or with a solution of alum. This is for the purpose of removing grease or fatty matter that adheres to the surface, and which would prevent attainment of success in printing. In other words, if 70 such matter were not removed, and a drawing be made upon the surface with a lithographic crayon, then, in "rolling up" with ink, not merely the stippling, but the entire surface would absorb the ink and the device 75 appear black in the print. In other words, the washing with dilute acid restores the stone to its original condition before the stipple ink was applied. The stone is now ready to receive the design, which is drawn thereon 80 with a lithographic crayon in the usual way.

For economy of labor, that is to say, to avoid making a drawing with the lithographic crayon, I may extend the above-described method of preparing the drawing surface as 85 follows: The stippled and acid-washed surface is treated with an ink-taking transparent, or translucent, substance of a fatty, or resinous, nature, such as asphaltum, for instance. This fatty or resinous substance, being in a liquid state, is poured over the entire surface, and then rolled with a roller so that it is evenly spread, and then the artist, by the use of a scraper, or bone, or pumice stone, scrapes off or removes, by abrasive action, at different points, as required, more or less of the thickness of the asphaltum coat, and thus leaves the points of the stippling entirely bare and clean at such points, or else 95 thinly covered with the asphaltum, the depth 100

of the latter being graduated correspondingly to the toning required for producing the print or picture.

It is to be understood, that when the points 5 of the stipples are bare they will not absorb ink, and hence will not print, and consequently the ink-taking substance only prints, thus producing the reverse effect which is produced by the use of the crayon on the 10 stone or plate.

Now for pictures requiring about eight or ten stones, several are treated with a fatty substance as described, while the rest are treated with the crayon. Those treated with a 15 fatty substance, as above described, contain light colors only, as the bare stipple points do not print and white dots only appear in the impression. Thus, this part is only suited for light color work. The darker colors 20 are treated on the several stones with the crayon in the usual manner.

It will be seen that by this method, the original uniform stipple tint is preserved and consequently a high grade picture can readily be produced. By treating the stone or 25 plate with an acid as above described, I am enabled to make any alterations or changes desired, as the original stipple remains intact and can be treated over and over again for 30 corrections, by first washing out with turpentine and then treating the washed out portion with the acid, so as to be in condition to be acted on by the crayon. Changes or corrections on the stone treated with the fatty 35 substance can be made by treating the faulty part with the solution of acid above referred to, then drawing on the bare stipples with the crayon.

Having thus fully described my invention, 40 I claim as new and desire to secure by Letters Patent—

1. The herein-described method of producing a lithographic printing surface, which consists in transferring to the grained surface of 45 a stone or plate capable of taking lithographic ink, an impression taken with acid-resisting ink from an ink-stippled surface, then etch-

ing the unprotected part of the stone or plate, next removing the ink stipple, and finally treating the stone with an acid substantially 50 as described.

2. The herein-described method of producing a lithographic printing surface consisting of graining the stone or plate, then forming thereon, by a transfer, an even stipple by 55 means of an acid-resisting ink, then etching the unprotected part of the stone or plate, then removing the ink stipple, and finally treating the stone with an acid, substantially 60 as described.

3. The herein described method for producing lithographic drawings, consisting of first graining the stone or plate, then forming thereon by transfer an even stipple by an acid-resisting ink, then etching the unprotected 65 part of the stone or plate, then removing the ink stipple from the stone, then treating the stone with an acid, and then forming the picture on the points of the stipple with the ordinary lithographic crayon, substantially 70 as described.

4. The herein-described method of preparing a lithographic printing surface and producing a drawing thereon, which consists in the following steps; first, transferring to the 75 grained surface of a lithographic stone, or plate, an impression taken with an acid-resisting ink from an ink-stippled surface; second, covering the stippled surface with asphaltum, or its equivalent; third, removing 80 the asphaltum, save such portion as adheres to the stipples; fourth, etching the unprotected part of the stone, or plate; fifth, removing the ink stipple; sixth, washing the surface with an acid, to remove fatty matter; 85 seventh, covering the surface with asphaltum or other ink-taking substance; and eighth, removing the asphaltum coat either wholly or partly, at the required points, according to the toning effect desired, as set forth.

FRANKLIN F. HAGGENMULLER.
